UNITED STATES PATENT OFFICE.

KARL CASTAN, OF PFORZHEIM, GERMANY.

RULING APPARATUS FOR CHARACTERS.

Application filed March 11, 1927, Serial No. 174,557, and in Germany July 22, 1926.

This invention relates to an apparatus for ruling for characters, especially so-called Egyptian characters used on drawings.

Apparatus have become known which 5 serve for writing characters of this kind, the main element of the apparatus consisting of one or several stencils which do not require ruled lines for the capital letters and small letters. These apparatus are not only very 10 expensive but also difficult to use, so that they generally are employed only by beginners and unskilled people, the skilled technical draftsman writing the Egyptian characters offhand with the aid of a nib the width 15 of which corresponds to the height of the characters. With this object in view the draftsman has first to ascertain the following measures: height of the capital letters and of the small letters, interval between the 20 lines and number of the pen, whereupon the heights and intervals have to be transferred with the rule and the lines have to be drawn with the T-square; all this requiring much difficult work.

25 This invention has for its object to considerably simplify the working method.

An embodiment of the invention is shown, by way of example, on the accompanying drawing, in which

30 Figs. 1 and 2 show each the apparatus in elevation.

Fig. 3 shows the cross section of a hole.

Fig. 4 shows an example of application.

A plate *a*, about 1,2 mms. thick and made 35 of celluloid or any other transparent material, has the shape of a parallelogram the left and right short sides *b* and *c* form with the upper and lower long sides at each corner an angle of 75°, at which angle the standard types, so-called Egyptian are inclined to 40 the horizontal. The short sides *b* and *c* serve to occasionally draw auxiliary lines by means of which the inclined position of the characters at the writing is controlled. On these 45 short sides *b*, *c* graduations are marked in which the distance between the lines is equal to a millimeter or to a centimeter so that without the aid of a set square and of an ordinary scale millimeter intervals can be marked or 50 horizontal straight lines in distances of millimeters can be drawn. The scales on the drawing show the millimeter divisions only in the first centimeter although the division is continued from one end to the other.

55 In plate *a* several hole systems are ar-

ranged and designated each in proximity to the foot line *f* on which they all begin, by 2,5; 3,5; 5; 7; 10; 14; 20; 28 respectively. These numerals correspond to the measurements of the height of the capital characters 60 in millimeters. The dividing holes belonging to one hole system are arranged the one above the other at 75°. The distance of the first and second hole from the foot hole is equal to the height of the small characters 65 and to the height of the capital characters. In each hole system the height of the capital characters is marked by two parallel straight lines *g* standing 75° to the horizontal line, and above these two lines *g* one single straight 70 line *h* indicates the average space between two lines. In order, however, that the line space may be selected smaller or greater than the average line space in the system, another hole is arranged at either side of each hole 75 system the one of these holes standing lower and the other hole higher than the system. The first hole indicates the line space which corresponds to the standard minimum measure which is selected so that the lines written 80 with this space appear to the eye just as continuous writing. On the plate *a* the three holes belonging to the system designated at the foot hole by "14" and designed for the three different line spaces are marked "minimum, average, maximum, line space".

For writing with character height "7" and shorter (right half of the plate *a*) the total height of a written line including the corresponding line space is several times marked 90 by holes spaced 75°, as these smaller writings are specially frequently used in whole lines in schedules, indexes and the like, so that the foot lines for several lines can be drawn without shifting of the ruler on which the table 95 *a* rests.

In all systems, with the exception of that for the smallest character height, the figures $\frac{1}{2}$; $\frac{3}{4}$; 1; 1,5; 2; 3; 4 are further marked. They indicate the thickness of the contours 100 of the characters in millimeters. The distance between the parallels *g* in one system corresponds to this size. The pens for writing Egyptian characters are known in commerce under the same figures.

105 Approximately at the center of plate *a* two hole systems are arranged the holes of which serve for the production of a greater number of lines spaced 4 and 5 millimeters or the multiple of 4 and 5 millimeters. The meas-

ure figures 4 and 5 with arrows indicate the measure of the hole distance in the vertical direction.

The scales on the short sides *b* and *c* begin at the height of the foot line *f* of the hole systems 6 centimeters being marked in upward direction and 1 centimeter in downward direction. It is thus possible to measure the line space or the distance from an existing 10 margin line in millimeters although the division holes existing in the hole system do not tally with the line spaces. Fig. 4 illustrates this by way of example. Characters of the height "10" have to be written between 15 two margin lines spaced 20 millimeters. In order to obtain the footline for the writing it is necessary to measure, with the aid of one of the scales on the short sides *b* or *c* from the upper margin line 15 millimeters in 20 downward direction or 5 mm. in upward direction from the lower margin line.

The hole cross section shown in Fig. 3 shows two different cones. The crater-shaped enlarged portion *i* serves to facilitate 25 the insertion and the narrower portion *k* serves to guide the pencil point during the ruling. If the distance between two holes is so short that their craters would merge the one into the other, one of the holes is made 30 on the horizontal, in preserving the distance in the vertical direction, as this is shown in the systems for the height 5; 3,5; 2,5 for the holes which indicate the height of the small characters on the plate *a*.

35 To use the instrument lay the lower long side *d* of the same on the ruler, insert a pencil in the correct hole and move the instrument under slight pressure onto the ruler along this ruler. The desired lines are then directly drawn on the drawing paper.

The hole systems are arranged on plate *a* so that the highest are at the middle whereby tipping of the instrument around the left or right lower corner in the direction of the 45 arrow A or B during the use is prevented.

The arrangement of the hole system under 75° has been selected in order to fix in the user's memory the angle measure of the inclination of the characters.

50 The parallel lines *g* between foot and head of the capital characters and indicating the thickness of the writing allow to discern and compare the size and thickness of the characters of the several hole systems so that the 55 selection of the writing adapted for the actual case is considerably facilitated.

I claim:—

1. A ruling instrument for writing consisting of a plate of transparent material and 60 having hole systems one for each height of the writing, each hole system comprising essentially division holes arranged the one above the others and designating respectively the vertical limits of small characters, capital characters and the line space, all the hole

systems beginning on one and the same foot line which is parallel to the long sides of said plate, there being two parallel straight lines inclined to the horizontal at the angle of inclination of the characters indicating the height of capital characters in each hole system, the distance between said lines being equal to the thickness of the lines forming the characters.

2. A ruling instrument for writing consisting of a plate of transparent material and having hole systems one for each height of the writing, each hole system comprising essentially division holes arranged the one above the others and designating respectively the vertical limits of small characters, capital characters and the line space, all the hole systems beginning on one and the same foot line which is parallel to the long sides of said plate, there being two parallel straight lines inclined to the horizontal at the angle of inclination of the characters indicating the height of capital characters in each hole system the distance between said lines being equal to the thickness of the lines forming the characters, and the line space indicated in each hole system by a straight line from the center to the center of the corresponding division holes.

3. A ruling instrument for writing consisting of a plate of transparent material and having hole systems one for each height of the writing, each hole system comprising essentially division holes arranged the one above the others and designating respectively the vertical limits of small characters, capital characters and the line space, all the hole systems beginning on one and the same foot line which is parallel to the long sides of said plate, there being two parallel straight lines inclined to the horizontal at the angle of inclination of the characters indicating the height of capital characters in each hole system the distance between said lines being equal to the thickness of the lines forming the characters, the line space indicated in each hole system by a straight line from the center to the center of the corresponding division holes, and two further division holes for a smaller and a greater line space arranged at either side of the hole system.

4. A ruling instrument for writing consisting of a plate of transparent material and having hole systems one for each height of the writing, each hole system comprising essentially division holes arranged the one above the others and designating respectively the vertical limits of small characters, capital characters and the line space, all the hole systems beginning on one and the same foot line which is parallel to the long sides of said plate, there being two parallel straight lines inclined to the horizontal at the angle of inclination of the characters indicating the height of capital characters in each hole

system the distance between said lines being equal to the thickness of the lines forming the characters, the line space indicated in each hole system by a straight line from the center to the center of the corresponding division holes, and two further division holes for a smaller and a greater line space arranged at either side of the hole system, several hole systems specially for writings which are frequently used linewise being arranged on said plate directly the one above the other.

5. A ruling instrument for writing consisting of a plate of transparent material and having hole systems one for each height of

the writing, each hole system comprising essentially division holes arranged the one above the others and designating respectively the vertical limits of small characters, capital characters and the line space, all the hole systems beginning on one and the same foot line which is parallel to the long sides of said plate, and there being scales on the short sides of the plate the zero point of each scale being situated at the height of said foot line of the hole systems.
